FASTENER FOR SHIRT COLLARS

Floyd A. Wiegman, Chicago, Ill.

Application March 20, 1935, Serial No. 12,036

4 Claims. (Cl. 24—81)

The invention relates generally to means for holding laundered articles of wearing apparel, such as shirts, in folded position and relates more particularly to a fastener to be applied to a permanently attached collar of a laundered shirt.

It is now common practice in commercial laundries to button the top or collar button on all collar attached shirts before folding the same in order that the collar may be retained in proper position. In all instances, but particularly when the collar has been heavily starched, buttoning of the top or collar button is difficult and tedious work, it causes wrinkles in the collar and makes additional hand finishing necessary. This all 10 raises the cost of laundering shirts. Furthermore, it is just as difficult for the user of the shirt to unbutton the top button as it is to button the same so that in doing so much time is lost and frequently results in a wrinkled and broken 15 down collar or the loss of a button.

It is a primary object of this invention, therefore, to provide a novel and improved fastener for securing the collar of a laundered shirt in proper position without the necessity of buttoning the top or collar button.

Another object of the invention is to provide a fastener of the character described which is quickly and conveniently applied without danger of wrinkling the collar and which is just as conveniently and quickly removed.

A further object is to provide a fastener of the character described which hooks back of the welt or seam formed on the edge of the collar thereby securely gripping the collar and preventing 35 accidental release.

Yet another object is to perfect a fastener of the character described which is extremely cheap and which is small and so located when attached as not to interfere with other means that might be employed to support or protect the collar.

Other objects and advantages will become apparent from the following detailed description taken in connection with the accompanying drawing, in which:

Fig. 1 is a fragmentary view showing a laundered permanently attached collar held in position by a fastener embodying the features of this invention.

Fig. 2 is a fastener attached to portions of a collar, the collar portions being in section better to show the manner in which the fastener grips the collar.

Fig. 3 is a full size elevational view of the fastener.

Fig. 4 is a side elevational view of the shirt shown in Fig. 1.

While the invention is susceptible of various modifications and alternative constructions, it is shown herein and will be described hereinafter in a preferred embodiment. However, it is not intended that the invention is to be limited thereby to the specific shape or construction disclosed but is intended to cover all modifications and alternative constructions falling within the spirit and scope of the invention as defined by the appended claims.

For purposes of disclosure, the drawing shows a shirt 5 having a permanently attached collar formed by a neckband 6 and an outer downwardly folded portion 7. Such collars are all usually formed along their edge with a seam or welt 8 which is slightly thicker than the remainder of the portion 7. When laundered and folded as is now the common practice, the collar forms a V, 10 with the fold 9, formed between the band 6 and the portion 7, extending outwardly and upwardly from the point where the ends of the collar come together. The pointed ends of the portion 7, 15 with the collar so folded, slope upwardly from the bosom of the shirt from front to rear, as best seen in Fig. 4, and even the front portion of the band 6 is inclined slightly from a perpendicular to the shirt front.

The fastener comprises a blank 10 of relatively 30 stiff cardboard or other suitable material shaped and slotted to form clamping means for engaging the end edges of the collar to secure the same against lateral spreading. While the blank may take various shapes, it is here shown as generally 35 round with the top end flattened, the blank being symmetrical with respect to a vertical center line thereof. Formed in the blank on opposite sides of the vertical center line are two apertures 11 generally oblong in shape and extending obliquely outwardly and upwardly. Extending obliquely outwardly and upwardly from each of the apertures 11 to the edge of the blank is a slit 12. Thus the blank 10 is divided into a lower or main portion 13 and an upper or tab portion 45 14 between which the opposite edges of the collar may be secured.

As a result of the apertures 11 and slits 12 the lower or main portion 13 may be said to have two oppositely disposed and upwardly extending portions 15, each forming one jaw of a clamping means. The tab 14 likewise has two oppositely disposed and downwardly extending portions 16 forming jaws complementary to those formed by the portions 15. In order further to enhance 50 55

the gripping action of the portions 15 and 16, the apertures 11 are so formed that the portions, particularly the portions 15, terminate in inwardly turned hooks 17. Herein this is obtained by the rounded ends of the apertures 11 and by extending the slits 12 from approximately the ends of the apertures. Preferably the apertures 11 are positioned with their longitudinal axis slightly less oblique to the vertical center line 10 of the blank than the slits 12. The blank may be formed with V notches at the outer ends of the slits to shorten the same without weakening the remainder of the blank.

The blank is attached to the collar by inserting the portions 15 into the fold formed by the neckband 6 and the portion 7 while the portions 16 engage the fold on the outside thereof so as to clamp one end of the collar securely between each set of jaws formed by the portions 15 and 16. The blank is conveniently and easily attached to the collar by flexing the tab 14 out of the plane of the main portion 13 thereby opening the jaws formed by the portions 15 and 16. When so attached the blank assumes a slightly 25 inclined position and with the slits 12 extending obliquely outwardly and upwardly the straight edges formed on the ends of the portions 15 and 16 by the slits lie parallel to the fold 9 of the collar so that there is good gripping action between the jaw portions and the collar. Not only 30 is there a firm gripping by the jaws, but, as best seen in Fig. 2, the hooks 17 engage in back of the welt 8 and thus so firmly secure the blank as to eliminate any possibility of accidental removal thereof. With the blank made of cardboard there is no danger that the hooks will pierce or tear the collar. The oblong apertures 11 should be of a size amply to accommodate the welt or seam 8 of the collar, as best seen in 35 Fig. 2. The blank when attached does not rest on the bosom of the shirt and thus does not in any way support or distort the collar, yet it is so small and is so positioned that it does not interfere with other blanks that might be applied 40 to support or protect the collar.

It is believed apparent from the foregoing that I have provided a simple, easily manufactured and inexpensive clamp which is readily and quickly attached to a laundered collar to secure the same without buttoning the top or collar button thereby materially reducing the cost of laundering the shirt and avoiding wrinkling of the collar both in the folding of the shirt and in the unfolding thereof by the user. While the clamp is advantageous and may be used to secure the collar regardless of the manner in which the shirt is folded, it is particularly advantageous when employed in the method of and with the machine for folding shirts disclosed in my co-pending application Serial No. 745,769, filed September 27, 1934. In that application I disclose a machine for folding a laundered shirt without buttoning any of the buttons except the top

one. Thus this clamp, when employed with the method disclosed in my prior application, enables a laundered shirt to be folded and packaged without buttoning a single button. As a result the shirt is without wrinkles, it can be put up 5 in a much shorter time and is ready to wear as soon as the package is removed without first unbuttoning the shirt or removing numerous pins.

I claim as my invention:

1. A fastener for securing the collar of a laundered shirt in closed position without buttoning the same comprising a thin resilient blank having two apertures therein and a slit extending outwardly from each aperture to the edge of the 15 blank defining cooperating hook jaws unpliant in the plane of the blank but laterally flexible to permit passing of an end edge of the collar, having a welt, between the jaws into the aperture and to grip the collar frictionally behind the welt when the welt has passed into the 20 aperture.

2. A fastener for securing the collar of a laundered shirt in closed position without buttoning the same comprising a thin blank having two 25 apertures therein shaped to receive the welt on the edge of a collar and a slit extending outwardly from each aperture to the edge of the blank defining for each aperture cooperating hook jaws unpliant in the plane of the blank, 30 one of said jaws being resilient and laterally flexible to permit passing of an end edge of the collar, having a welt, between the jaws into the aperture and to grip the collar frictionally behind the welt when the welt has passed into the 35 aperture.

3. A fastener for securing the collar of a laundered shirt in closed position without buttoning the same comprising a thin resilient blank having two elongated apertures therein and a slit 40 extending obliquely outwardly and upwardly from each aperture to the edge of the blank defining cooperating hook jaws unpliant in the plane of the blank but laterally flexible to permit passing of an end edge of the collar, having a 45 welt, between the jaws into the aperture and to grip the collar frictionally behind the welt when the welt has passed into the aperture.

4. A fastener for securing the collar of a laundered shirt in closed position without buttoning the same comprising a cardboard blank symmetrical with respect to a vertical center line having two apertures therein large enough to receive the welt on the edge of a collar and a slit extending obliquely outwardly and upwardly 50 from each aperture to the edge of the blank defining cooperating hook jaws unpliant in the plane of the blank but laterally flexible to permit passing of an end edge of the collar, having a 55 welt, between the jaws into the aperture and to grip the collar frictionally behind the welt when the welt has passed into the aperture.

FLOYD A. WIEGMAN.
